Primary Examiner — Charles Hanson(74) Attorney, Agent, or Firm — Conley Rose, P.C.; Rodney B. Carroll(57) CLAIM

The ornamental design of a nasal support device, substantially shown and described.

DESCRIPTION

FIG. 1 is a top perspective view of an embodiment of a nasal support device;

FIG. 2 is a bottom perspective view thereof;

FIG. 3 is a first side view thereof;

FIG. 4 is a second side view thereof, wherein the second side view is opposed to the first side view;

FIG. 5 is a third side view thereof;

FIG. 6 is a fourth side view thereof, wherein the fourth side view is opposed to the third side view;

FIG. 7 is a top view thereof; and,

FIG. 8 is a bottom view thereof.

The broken line showing is included for the purpose of illustrating unclaimed subject matter and forms no part of the claimed design.
